SHOE AND METHOD OF MAKING THE SAME

Seymour Troy, New York, N. Y.

Application January 30, 1932, Serial No. 589,777

2 Claims. (Cl. 36—57)

This invention relates to shoes and a method for making them, and, more specifically, to slippers, pumps and the like which have a relatively low opening for receiving the foot.

In general it is an object of this invention to provide a method and product resulting therefrom of the character described which is simple and economical of construction, which can be expeditiously and conveniently manufactured and assembled.

Another object of the invention is to provide a shoe which shows neither stitching nor tape along its upper edge.

Another object is to provide a shoe, the upper of which extends over the upper edge and hides all means for securing the upper to the lining.

Other objects of the invention will in part be obvious and will in part appear hereinafter.

The invention accordingly comprises the several steps and the relation and order of one or more of such steps with respect to each of the others, and the article possessing the features, properties, and the relation of elements, which are exemplified in the following detailed disclosure, and the scope of the application of which will be indicated in the claims.

For a fuller understanding of the nature and objects of the invention reference should be had to the following detailed description taken in connection with the accompanying drawing, in which:

Fig. 1 is a perspective view of a shoe embodying the invention;

Fig. 2 is a cross-section of a portion of the shoe shown in Fig. 2 taken along the lines 2—2; and

Fig. 3 is a cross-section of an upper, a lining and a binding tape at one step in the process of making the shoe shown in Fig. 1.

The appearance which a shoe presents is an important feature in the marketing and sale of footwear. It is highly desirable that the structural elements be hidden from view and that in general the product look simple and neat as far as details which are not purely decorative are concerned. The present invention supplies a shoe wherein the outer covering, known as the upper, is firmly secured to the lining by stitching immediately adjacent the rim surrounding the ankle, but which, nevertheless, shows no stitching either inside or outside. Furthermore, although binding tape is used in the shoe construction, it is invisible. The upper seems merely to be folded over the rim and there is no sharp edge within the shoe to wear against hose.

In the embodiment of the invention shown in

the drawing the upper 11 of the shoe 10 extends over the edge or topmost rim 12 and is so stitched to the lining 13 that although a seam is visible on the inside of the shoe, the stitches are completely hidden. In the building of the shoe 60 a lining 13 is secured between the upper 11 and a binding tape 14 by stitching 15 along a common edge, as shown in Fig. 3. The upper is then drawn up and over the common edge and brought down on the other side until it is again parallel 65 and in contact with the lining except for that portion bent over the common edge as shown in Fig. 2.

The binding tape 14, which is preferably used to impart a certain desirable stiffness and form- 70 retaining property to the upper edge of the shoe, is thus shown to be positioned between the upper and the lining, and hidden from view by the enveloping fold of the upper. It will be apparent that the surfaces of the upper and the lining 75 which are to be seen in the completed shoe must have been face-to-face during the stitching so that when the upper is drawn or folded over the top in the manner described, these surfaces may be exposed. If desired, an adhesive in the space 80 16 may further unite the inner lining and upper and a canvas stiffener or interlining of the usual type may be employed.

In a shoe made by the above process the stitching and tape are entirely invisible. There is no 85 outward bulge of tape. The final product is simple, smart and attractive.

Since certain changes in carrying out the above process, and certain modifications in the article which embody the invention may be made without departing from its scope, it is intended that all matter contained in the above description or shown in the accompanying drawing shall be interpreted as illustrative and not in a limiting 95 sense.

It is also to be understood that the following claims are intended to cover all of the generic and specific features of the invention herein described, and all statements of the scope of the 100 invention which, as a matter of language, might be said to fall therebetween.

Having described my invention, what I claim as new and desire to secure by Letters Patent is:

1. In a shoe, in combination with an upper and 105 a lining a binding tape stitched to said upper and said lining, said parts being so arranged and the upper being so folded as to hide from view all of said stitching and all of said binding tape, and means also completely hidden from view by said 110

upper and said lining and adapted to hold said upper and said lining against relative movement.

2. A shoe comprising an upper, a lining, and a binding tape stitched together, the parts being so arranged and the upper being so folded as to completely hide from view said stitching and all of said binding tape, the upper and lining being so

positioned and held against relative movement that the upper extends partially within the inner portion of the shoe, the lining of the shoe and every means of attaching the lining to the upper being completely invisible when the shoe is worn. 80
